VANE TYPE HYDRAULIC MOTOR

Oscar E. Rosaen, Detroit, Mich., assignor, by direct and mesne assignments, to The New York Air Brake Company, New York, N. Y., a corporation of New Jersey

Application May 28, 1949, Serial No. 96,020

3 Claims. (Cl. 121—92)

1

The present invention relates to hydraulic motors and specifically to hydraulic motors of the vane type and has among its objects the provision of a motor having means to control the vane movement.

Another object is to provide means for controlling vane movement "in" and "out" and in either direction of movement of the rotor of such motors.

Still other objects and advantages will be apparent to those skilled in the art upon reference to the following description and the accompanying drawings in which

Fig. 1 is a longitudinal sectional view of the motor as if on line 1—1 of Fig. 2.

Fig. 2 is a section on line 2—2 of Fig. 1.

Fig. 3 is a partial longitudinal central section showing a different form of control valve.

Fig. 4 is a view in elevation of the rotor face of one of the flow directing plates.

Fig. 5 is a section on line 5—5 of Fig. 4.

Fig. 6 is a section on line 6—6 of Fig. 4.

Fig. 7 is a section on line 7—7 of Fig. 4.

Fig. 8 is a perspective view of the motor ring.

Fig. 9 is a view in elevation of the valve of Fig. 1.

Fig. 10 is a perspective view of one of the vanes.

Fig. 11 is a detail of the construction shown in Fig. 3.

Fig. 12 is a partial section on the line 12—12 of Figure 1.

In the drawings, referring particularly to Fig. 1, the motor is made up of two end members 20 and 21 similar in most respects, each being provided with a cored annular chamber 20A—21A into which lead conduits 20B—21B. Each is provided in its inner face with a seat 20C—21C for a flow directing plate to be particularly described later and each is provided with lugs 20D—21D and bolts or screws by means of which they may be fixed together, a suitable gasket being used to prevent leakage. Each of the members is provided also with a seat 20E—21E in its outer face around the central opening for the shaft 22. The shaft 22 traverses members 20 and 21 and the inner end thereof is supported in a suitable bearing 22A mounted in a cap 22B fixed upon the seat 21E. The shaft extends through member 20, being supported therein in a suitable bearing 22C and surrounded by an oil seal 22D fixed upon seat 20E. The bearing 22C and oil seal being maintained in place by the plate 23.

The extended end of shaft 22 is adapted in any suitable fashion for power take-off.

2

Each of the members 20 and 21 is as stated above provided with a seat 20C—21C for a flow directing plate. These flow directing plates indicated at 24 and 25 are shown in detail in Figs. 5 to 7 inclusive, the two plates being identical, but when in position, become "right" and "left." Each consists of a thick disc portion 24A provided with a central opening 24B surrounded on one face of the disc by a hub portion or flange 24C, internally threaded near its end. Each has in its outer, or hub face, an annular channel 24D. Each has cut in its inner face near the periphery arcuate openings 24E and 24F arranged in pairs, the openings 24E being cut through to open into channel 24D and the openings 24F being merely chambers.

Each is also provided with smaller openings near the central opening, these also being arranged in pairs; of these, the openings 24G, 20 radially inward of the openings 24E, extend through the disc and appear in the outer face in that part within the inner perimeter of channel 24D. The other members of the pairs 24H do not extend through the disc but are merely chambers. Each of the openings 24G and 24H is provided with an extension extending circumferentially a short distance on either side in the form of a short channel tangent to its opening at the outer side thereof.

Further, each of the discs is provided with a passage 24J open to the outer, or hub face, of the disc and extending to the central opening 24B near the inner face of the disc where it opens to a narrow annular channel 24K. This passage is provided with a check valve and located substantially midway between openings 24G and 24H.

Further, in the inner face of each of the discs there is provided a channel 24M connecting all of the openings 24G and 24H. This channel 24M is of capillary dimensions, preferably of the order of about a square 64th of an inch.

The plates 24 and 25 are, as stated above, seated in the end members 20 and 21 on the seats 20C and 21C and in face to face relation with an opening 24E in one opposite a chamber 24F in the other. They are held, each in its end member by a suitable nut 26 externally threaded and coacting with the internal threads in openings 24B.

Splined on shaft 22 and arranged to rotate between plates 24 and 25 is a rotor 27, this being shown (in Fig. 1) as provided with hub portions 27A extending into and having bearings in plates 24 and 25. The rotor consists of a 55 thick disc having substantially radial slots 27B

with an equal number of through passages 27C radially inward of the slots and connected by radial passages 27D thereto. In addition, a plurality of smaller through passages 27E are located radially inward of the passages 27C, these being so arranged as to be open to the channel 24K in the plates 24 and 25.

In each of the slots 27B is mounted a vane 29 such as that shown in Fig. 10, which consists of a pair of hardened steel leaves 29A and 29B of equal dimensions and the combined thickness slightly less than the corresponding dimension of a slot 27B. Each of the leaves has three of its edges at one face beveled, and these beveled edges are placed together when assembling a pair so as to provide channels 29C at the lateral edges of a vane and a chamber 29D at one end, this end being the outer end when the vane is assembled with the rotor 27.

Surrounding the rotor 27 is a hardened steel ring 28 dimensioned to space the plates 24 and 25 so as to afford a running fit for the rotor 27. This ring is circular and outwardly of the same size as the plates 24 and 25, its inner periphery is, however, formed to provide a plurality of partly circular sections or zones of which two diametrically opposite ones, indicated at 28A, are formed on a radius of a length equal to or slightly greater than the radius of the rotor and vanes when the latter are moved to their inner position in the slots.

Between the zones 28A and diametrically opposite each other are two zones 28B, partly circular, of which the radius is somewhat greater. Each of the zones 28A and 28B is somewhat less than 90° in extent, and between them, the ring wall is sloped as shown at 28C, so as to provide an easy transition from one zone to the next. Further, parallel with the zones 28A, through passages 28D are provided in the ring radially outward of such zones.

Mounted in chambers 20A and 21A and arranged to cover the channels 24D in the plates 24 and 25 are valve members 30 and 31. Each of these, as shown, consists of a flat ring 30A provided with two diametrically oppositely located groups of openings 30B and two small arcuate plates 30C of such size as to cover each one of the groups of openings 30B. These plates 30C are fixed to headed stems 30D which extend through plate 30A and carry under compression, springs 30E. The valve members 30 and 31 are arranged in the chambers 20A and 21A as to open under further compression of springs 30E toward the rotor 27. The valve members 30 and 31 are maintained in position over the channels 24D by means of light springs 32 of which there are a plurality equally spaced about the periphery of the valve members, only one being shown.

In the form of motor indicated in Figs. 3 and 11, the construction may be similar to that just described but a different form of valve is shown. In this construction, the valves 30 and 31 are shown as annuli of rubber or other suitable flexible and resilient material. Each valve consists of two flat rings 30A and 30B, one within the other with their adjacent edges pressed together. These rings are so mounted that the supporting and fixing surfaces at the inner face of the valve extend over more of the valve surface than do the supporting surfaces on the outer face of the valve. The flexible valve rings will thereby offer greater resistance to fluid flow inward than outward.

The outermost of the two valve rings 30A is

clamped between one of the flow directing plates 124 and 125 and a suitable portion of one of the end members 120 and 121. The inner ring 130B is held in place by means of a plate 124 or 125 and a ring member 135 fixed in an end member. This ring member 135 is shown in Fig. 11 to consist of a perforated sheet metal ring provided with outwardly extending projections 135A adapted to contact the valve ring.

The structure of Fig. 3 functions in the same manner as that of Fig. 1.

In the operation of the motor, assuming that oil under pressure is being supplied to inlet 21B (Fig. 1), the oil enters chamber 21A and, through passages 24G in plate 25, enters passages 27C and through passages 27D flows into the slots 27B of the rotor, thus forcing the vanes 29 out against the ring 28.

As the pressure in chamber 21A is built up, it finally overcomes the tension of springs 30E of the valve member and oil is admitted through openings 30B to the passages 24E and to the rotor chamber at the beginning of zones 28B. With the rotation of the rotor this intervane oil is carried to the ends of the zones 28B and flows out through passages opposite chambers 24F in plate 24 opening the valve 30 against the action of its springs 32.

While this action is taking place, some of the oil from chamber 21A flows through the inwardly opening valve controlling passage 24J in plate 25 and to the annular chamber 24K which communicates along the rotor splines or through suitable small passages 27E with the chamber 24K in plate 24 from which it cannot flow through the other valved passage 24J since this also opens inwardly. However, due to the clearances necessary to permit free rotation of the rotor, there is always a small flow of oil from 24G to 24H and from chambers 24K to outlets 24H, since there is a large drop in pressure between these two points. There is also a minute flow through the channels 24M connecting all of the openings or chambers 24G and 24H. The effect of this directing of the oil into the vane slots is to maintain the pressure under the vanes.

As the rotor 27 turns under the influence of pressure fluid entering passage 24E, the greatest pressure between vanes will be between those in the positions V and X (see Fig. 12) and since more of vane X is exposed thereto, the turning effort will be in the direction of the arrow. As soon, however, as the vane W has moved to the X position, the pressure between vanes X and Y decreases and there will be a still further decrease between Y and Z, this intervane pressure dropping to substantially zero as vane Z reaches the discharge passage 24F.

However, the high intervane pressure would, unless prevented from doing so, force the vanes down into the slots 27B. So means is provided to prevent too fast a drop in pressure in the vane slots due to leakage through the small clearances at the side faces of the rotor and through the rotor bearings.

This means is the means for supplying fluid under pressure to the annular chambers 24K and the small groove 24M. The fluid in chambers 24K, of course, tends to form a counterflow against the flow out of the vane slots while the groove 24M tends to equalize the pressures in the slots at all times. In other words, the vanes 29 must at all times be positively urged out against ring 28 but the high pressure should

not be maintained because it is both unnecessary and objectionable except in zones 28B.

In the present construction the drop in pressure in the vane slots substantially parallels the drop in pressure between the vanes but is maintained at a low point in zones 28A.

While the operation has been described with the assumption that fluid is introduced into chamber 21A, it is obvious that reversal of flow with introduction of fluid into chamber 20A will be accomplished in similar fashion since the two plates 24 and 25 and associated parts are identical.

The present application is a continuation in part of the subject matter of application Serial No. 715,181, filed December 6, 1946, now Patent No. 2,521,997, granted September 12, 1950.

Now having described the invention and the preferred embodiment thereof, it is to be understood that said invention is to be limited, not to the specific details herein set forth and described, but only by the scope of the claims which follow.

I claim:

1. A fluid pressure motor of the vane type comprising in combination a rotor having radial slots arranged in circular series adjacent its periphery, and sleeve-like hub extensions spaced radially inward from the inner ends of said slots; a housing comprising a ring spaced from and encircling said rotor, and having an inner contour adapted to cause said vanes to move radially and pass through alternate working and idle zones between the rotor and ring as the rotor turns, and side members which seal against the side faces of said rotor and the radial edges of the vanes and in which the hub like portions of the rotor are journaled, there being an annular groove encircling each hub like portion, said enclosing means having passages for supplying fluid under pressure from a common source to the inter-vane spaces in the working zones, to the slots at the inner ends of the vanes and to said annular grooves; and pressure-differentiating means for reducing the pressure of liquid delivered to said inter-vane spaces as compared with the pressure of liquid delivered to said slots and to the grooves whereby leakage from the inter-vane spaces is resisted by the superior fluid pressure in the slots, and the escape of liquid from the slots along said hub like portions is resisted by the liquid under pressure admitted to said grooves and serving to supply such leakage along the hub-like portions as can occur.

2. In a fluid actuated motor of the vane type having a rotor chamber, arranged to provide a plurality of arcuate active driving zones and a plurality of arcuate intermediate idle zones, 5 a rotor in said chamber, said rotor being provided with radially arranged slots and with radially slideable vanes in said slots, and means for introducing fluid under pressure at the beginning of said driving zones and simultaneously to said slots under said vanes, said introducing means consisting of arcuate passages substantially coinciding with the arc of transition from a driving to an idle zone, the passages leading to said slots being connected to each other by a passage of capillary size.

3. In a vane type fluid motor, a slotted rotor with substantially radially movable vanes in said slots, a pair of flow directing plates adjacent said rotor and provided with passages leading 10 to the intervane spaces and with other passages leading to said slots under said vanes, said plates also provided with an annular channel in that face away from said rotor and open to the first mentioned passages, a housing for said 15 rotor and plates and consisting of end members each provided with an annular fluid chamber, one of said chambers constituting a fluid inlet and the other a fluid outlet, and a valve member in each of said chambers, said valve member consisting of an annular plate adapted to open and close the annular channel in a flow directing plate, each of said annular plates being provided with a spring actuated valve 20 opening toward said channel, and spring means 25 resisting the movement of said annular plate away from said channel.

OSCAR E. ROSAEN.
